SPINNING, TWISTING, AND LIKE APPARATUS

Ralph Ragan, Atlanta, Ga.

Application November 15, 1949, Serial No. 127,283

16 Claims. (Cl. 57—67)

1

This invention relates to spinning, twisting and like apparatus, and more particularly to improved mechanism to replace the spinning rings, travelers, flyers, throwers and the like on present forms of spinning and twisting machines.

In a present form of spinning and twisting apparatus known and used in the art, roving or fibers are fed through drawing rolls, thence through a thread guide centered over the revolving spindle, thence through a traveler slidably mounted on a spinning ring, and thence at right angles from the traveler to the spool or bobbin which revolves with the spindle. The rotation of the spindle wraps the yarn around the bobbin and the yarn carries the traveler forward around the ring, but the friction of the traveler sliding on the ring causes it to lag behind the speed of the spindle so that the traveler twists the roving or fibers into a thread. In starting up on an empty bobbin, ends are broken down due to the 20 yarn pulling closer to dead center when the rotation of the bobbin tries to make the traveler move forward around the ring. The traveler causes greater or less tension on the yarn depending upon the weight of the traveler and its area of contact with the spinning ring, and it is therefore necessary to change weights and sizes of travelers when different counts of yarn are produced. The surface speed of the traveler is quite limited and the life of a traveler is comparatively short. Oil or grease used to lubricate the rings and travelers soils the thread when an end breaks down and whips against these and other portions of the machine.

It is an object of my invention to provide mechanism which will eliminate or minimize the above noted difficulties.

Another object of my invention is to provide mechanism which makes it possible to run spinning and twisting frames and like apparatus at 40 speeds faster than is now permissible.

Another object of my invention is to provide apparatus which can be installed upon prior art spinning, throwing and twisting frames now in use by making minor changes and adjustments therein.

Another object of my invention is to provide apparatus upon which both twisting and cable twisting operations can be performed simultaneously.

Another object of my invention is to provide apparatus which is inexpensive to manufacture, durable in construction and efficient in operation.

Other and further objects and advantages of my invention will be apparent from the following description taken in connection with the accompanying drawing in which like characters of reference designate corresponding parts throughout the several views, and wherein:

2

Fig. 1 is a top plan view showing apparatus embodying my invention.

Fig. 2 is a cross-sectional view taken along the line 2—2 in Fig. 1.

5 Fig. 3 is a cross-sectional view taken along the line 3—3 in Fig. 1 and showing a detail.

Fig. 4 is a fragmentary side view taken along the line 4—4 in Fig. 1 and showing a detail.

10 Fig. 5 is a cross-sectional view taken along the line 5—5 in Fig. 1 and showing a detail.

Fig. 6 is a schematic view showing an arrangement of apparatus embodying my invention.

In the embodiment of my invention chosen for illustration, a spindle 10 carries the spool-driving lugs 11 and a disc 12 mounted for rotation therewith and upon which the spool or bobbin 13 rests. Surrounding the bobbin 13 is a pot 14 having an open upper end and a lower end which is closed except for a central bore provided with bronze bushing 15 through which the spindle 10 extends. The side walls of the pot 14 are provided on the inside thereof with diametrically opposed keys 16, 16', 16'', 16''' arranged for engagement in keyways or slots 17, 17', 17'', 17''' respectively, in the periphery of the disc 12.

A main bearing 18 is arranged with its inner race 19 supporting the pot 14 and its outer race 20 carried by a housing 21. The pot 14 is aligned with the spindle 10, and then the bearing housing 21 is secured, as by clamps 22, 22', or otherwise fastened to the flanged bushing 22'' which is set-screwed in place of the conventional ring on the conventional ring rail 23.

A thread guide bearing 24 has its inner race 25 seated on the outer side wall of the pot 14 near the top thereof, and the outer race 26 of this bearing carries the ring shaped support rim 27 which lies flush with the open upper end of pot 14, and also serves as a lubrication seal in the sealed-for-life type anti-friction bearing. Mounted upon the support rim 27 at diagonally opposite positions are the thread guides 28, 28' through which the yarn 29 passes to the bobbin 13. An even number of diagonally disposed thread guides are used to distribute the weight evenly to maintain balance in the pot 14. The thread guides 28, 28' are formed in the shape of elongated hooks which are set at an angle, as shown in Fig. 1, varying somewhat from a right angle to the radius of the pot, so that as the diameter of the package builds up on the bobbin 13 the thread passes over different positions on the guide and this prevents thread cutting which is so objectionable in a traveler where the thread runs in only one position.

Also mounted upon the support rim 27 are a pair of upstanding wind-vanes 30, 30' which are diametrically disposed and spaced 90° from the thread guides 28, 28' so as to maintain balance 60 in the pot 14. By means of the key-hole slots in

their bases, as shown in Fig. 1, these vanes are quickly and easily interchangeable with vanes of different sizes.

In addition, a pair of flexible brake arms 31, 31' are attached to the support rim 27 at diagonally opposite positions chosen to maintain balance in the pot 14. The brake arms 31, 31' are provided with brake shoes 32, 32', respectively, which are pressed against the wall of the pot 14 when the pot is at rest and are thrown outwardly against a stop 33, when the pot attains a predetermined speed of rotation.

In operation, the yarn or thread 29 passes through a thread guide 28 to the spool 13 when the machine is started; and, as soon as the spindle comes up to approximately one-half full speed, the brake shoes 32, 32' disengage so that the wind vanes 30, 30' cause the support rim 27 and associated parts mounted thereon to lag behind the speed of the spindle and take up delivery of the thread without jerking. It will also be apparent that this arrangement will permit starting without breaking down any ends of the thread being twisted, because the thread guide does not put any stress on the thread until the brakes are released. Also, in stopping, the brake shoes again engage the pot when approximately one-half speed has been reached and prevent ballooning of the thread by causing the thread guide to rotate at the same speed as the pot. In this connection, means should be provided for starting and for stopping the delivery rolls when the spindles reach one-half speed.

No oil or grease is used inside the pot, and the bearings 24 are of the sealed-for-life type so that no oil soiling will occur. Lint or fly which may get into the pot 14 is brought to the top by the disc 12 when the machine traverses, and this foreign matter is thrown outwardly from the pot by centrifugal force when the upper edge of the disc projects slightly above the upper rim of the pot at the limit of the traverse. The disc 12 rides up on the keys 16 to sweep the pot clean, and this also serves as a centering support to keep the pot concentric with the spindle. The wind vanes keep an even tension on the thread; and as the diameter of the package increases the thread passes to a different position on the thread guides set at an angle to prevent thread cutting.

In Fig. 6 I have shown an arrangement for simultaneous twisting and cable twisting on a single machine. Spools 13 and 13' are filled with thread or fibers wound parallel, and the thread from these two spools passes upwardly through center thread guides 34, 34', respectively, being pulled off from the spools so as to cause the thread guides 28 to travel at a speed faster than the spindles and twist the fibers thus thrown off into a cord. These cords are carried up over delivery rolls 35, 35' and then pass through center thread guide 34' down to the third spindle where they are twisted into a single cable cord and wound onto the spool 13'.

Many modifications, adaptations and changes can be made in the embodiment shown without departing from the scope of my invention as defined in the appended claims.

I claim:

1. In apparatus of the class described, a spindle, thread guide support means mounted for rotation with said spindle, said support means being also mounted for axial movement with respect to said spindle, an anti-friction bearing seated on said support means, and a thread guide carried by said anti-friction bearing.

2. In apparatus of the class described, a spindle, thread guide support means mounted for rotation with said spindle, said support means being also mounted for axial movement with respect to said spindle, an anti-friction bearing seated on said support means, a support rim carried by said anti-friction bearing, and a thread guide mounted on said rim.

3. In apparatus of the class described, a spindle, thread guide support means mounted for rotation with said spindle, said support means being also mounted for axial movement with respect to said spindle, an anti-friction bearing seated on said support means, a support rim carried by said last mentioned anti-friction bearing, a thread guide mounted on said rim, and a wind vane attached to said rim to cause said thread guide to lag behind the speed of said spindle.

4. In apparatus of the class described, a spindle, an open top pot mounted for rotation with said spindle, said pot being also mounted for axial movement with respect to said spindle, an anti-friction bearing seated on said pot adjacent the top thereof, a support rim carried by said anti-friction bearing, and a thread guide mounted on said rim.

5. In apparatus of the class described, a spindle, thread guide support means mounted for rotation with said spindle, a flanged bushing mounted for axial movement with respect to said spindle, an anti-friction bearing secured to said flanged bushing, said support means being carried by said anti-friction bearing, an anti-friction bearing seated on said support means, a support rim carried by said last mentioned anti-friction bearing, and a thread guide mounted on said rim, said thread guide being in the shape of an elongated hook and set at an angle less than a right angle to the radius of said support means.

6. In apparatus of the class described, a spindle, thread guide support means mounted for rotation with said spindle; a flanged bushing mounted for axial movement with respect to said spindle, an anti-friction bearing secured to said flanged bushing, said support means being carried by said anti-friction bearing, an anti-friction bearing seated on said support means, a support rim carried by said last mentioned anti-friction bearing, a thread guide mounted on said rim, and a brake arm mounted on said rim and carrying a brake shoe for engagement with said support means to cause said rim to rotate with said thread guide support means at low speed, said brake arm being operable by centrifugal force to release said shoe from said thread guide support means at a predetermined speed.

7. In apparatus of the class described, a spindle, thread guide support means mounted for rotation with said spindle, a flanged bushing mounted for axial movement with respect to said spindle, an anti-friction bearing secured to said flanged bushing, said support means being carried by said anti-friction bearing secured to said flanged bushing, an anti-friction bearing seated on said support means, a support rim carried by said last mentioned anti-friction bearing, a thread guide mounted on said rim, a brake arm mounted on said rim and carrying a brake shoe for engagement with said support means to cause said rim to rotate with said support means at low speed, said brake arm being operable by centrifugal force to release said shoe from said support means at a predetermined speed, and an upstanding wind vane removably attached to said rim to cause said thread guide to lag behind the

speed of said spindle when said brake shoe is not in engagement with said support means.

8. In apparatus of the class described, a spindle, thread guide support means mounted for rotation with said spindle, a flanged bushing mounted for axial movement with respect to said spindle, an anti-friction bearing secured to said flanged bushing, said support means being carried by said anti-friction bearing secured to said flanged bushing, an anti-friction bearing seated on said support means, a support rim carried by said last mentioned anti-friction bearing, a thread guide mounted on said rim, said thread guide being in the shape of an elongated hook and set at an angle less than a right angle to the radius of said support means, a brake arm mounted on said rim and carrying a brake shoe for engagement with said support means to cause said rim to rotate with said support means at low speed, said brake arm being operable by centrifugal force to release said shoe from said support means at a predetermined speed, and a wind vane removably attached to said rim to cause said thread guide to lag behind the speed of said spindle when said brake shoe is not in engagement with said support means.

9. In apparatus of the class described, a spindle, an open top pot mounted for rotation with said spindle, a flanged bushing mounted for axial movement with respect to said spindle, an anti-friction bearing secured to said flanged bushing, said pot being carried by said anti-friction bearing, an anti-friction bearing seated on said pot, a support rim carried by said last mentioned anti-friction bearing, a thread guide mounted on said rim, a brake arm mounted on said rim, a brake shoe mounted on said arm for engagement with said pot to cause said rim to rotate with said pot at low speed, said brake arm being operable by centrifugal force to release said shoe from said pot at a predetermined speed, and a wind vane attached to said rim to cause said thread guide to lag behind the speed of said spindle when said brake shoe is not in engagement with said pot.

10. In apparatus of the class described, a spindle, thread guide support means mounted for rotation with said spindle, an anti-friction bearing seated on said support means, a thread guide carried by said anti-friction bearing, brake means carried by said bearing for engagement with said support means at low speed to cause said thread guide to rotate with said support means, and means to cause said thread guide to lag behind the speed of said spindle when said brake means is not in engagement with said support means.

11. In apparatus of the class described, a spindle, thread guide support means mounted for rotation with said spindle, an anti-friction bearing seated on said support means, a thread guide carried by said anti-friction bearing, a brake arm carried by said bearing and having a brake shoe for engagement with said support means to cause said guide to rotate with said support means at low speed, said brake arm being operable by centrifugal force to release said shoe from said support means at a predetermined speed.

12. In apparatus of the class described, a spindle, thread guide support means mounted for rotation with said spindle, an anti-friction bearing seated on said support means, a thread guide

carried by said anti-friction bearing, a brake arm carried by said bearing and having a brake shoe for engagement with said support means to cause said guide to rotate with said support means at low speed, said brake arm being operable by centrifugal force to release said shoe from said support means at a predetermined speed, and a wind vane attached to said bearing to cause said thread guide to lag behind the speed of said spindle when said brake shoe is not in engagement with said support means.

13. In apparatus of the class described, a spindle, thread guide support means centered about said spindle for rotation therewith and for axial movement relative thereto, driving means carried by said spindle to drive said support means by said spindle, an anti-friction bearing mounted on said support means, and a thread guide carried by said anti-friction bearing.

14. In apparatus of the class described, a spindle, thread guide support means centered for rotation with said spindle, said support means being mounted for axial movement relative to said spindle, driving means carried by said spindle and having means for cooperation with said support means to drive said support means by said spindle, an anti-friction bearing mounted on said support means, and a thread guide carried by said anti-friction bearing.

15. In apparatus of the class described, a spindle, an open top pot centered for rotation with said spindle, said pot being mounted for axial movement relative to said spindle, a plurality of keys fixed inside said pot, driving means carried by said spindle and having keyways for cooperation with said keys to drive said pot by said spindle, an anti-friction bearing mounted on said pot, and a thread guide carried by said anti-friction bearing.

16. In apparatus of the class described, a spindle, an open top pot centered about said spindle for rotation therewith and for axial movement relative thereto, a key fixed inside said pot, driving means carried by said spindle and having a keyway for cooperation with said key to drive said pot by said spindle, said driving means including a disc fitted closely inside said pot to clean extraneous matter from said pot upon relative axial movement between said pot and said spindle, an anti-friction bearing seated on said pot, and a thread guide carried by said anti-friction bearing.
